UNITED STATES PATENT OFFICE

152,775

DESIGN FOR AN EXTENSIBLE BAND FOR A
WATCH BRACELET OR SIMILAR ARTICLEHans J. Duester, Chicago, Ill., assignor to himself
and John Major, Chicago, Ill.

Application September 3, 1948, Serial No. 148,446

Term of patent 14 years

(Cl. D45—4)

To all whom it may concern:

Be it known that I, Hans J. Duester, a citizen of the United States, residing at Chicago, in the county of Cook and State of Illinois, have invented a new, original, and ornamental Design for an Extensible Band for Watch Bracelet or Similar Article, of which the following is a specification, reference being had to the accompanying drawings, forming a part thereof.

In the drawings:

Figure 1 is a bottom plan view of an extensible band for a watch bracelet or similar article;

Figure 2 is a top plan view of the band, showing my new design;

Figure 3 is an enlarged fragmentary view of a section of the coiled portion of the band illustrating the details of the design; and

Figure 4 is an enlarged cross sectional view taken on the line 4—4 of Figure 1.

I claim:

The ornamental design for an extensible band

for a watch bracelet or similar article, as shown and described.

HANS J. DUESTER.
